UNITED STATES PATENT OFFICE

2,615,451

CROSS FEED CUTTER

John F. Halstead, Brooklyn, N. Y., assignor to
 International Cigar Machinery Company, a corporation of New Jersey

Application February 15, 1945, Serial No. 578,042

5 Claims. (Cl. 131—29)

1

This invention relates to an improved method and apparatus for cutting the filler tobacco for bunch charges, and is intended for the cutting of bunch lengths from which cigar bunches having blunt head ends and tapered tuck ends may be formed. More particularly the invention relates to cigar machines of the type wherein bunch lengths are cut from a stream of long filler tobacco and assembled to form a column of tobacco from which bunch charges are separated and wrapped within a binder to form a cigar bunch whose ends are squeezed to the required shape. This type of machine is shown in the Bronander Patent 1,740,571, issued December 24, 1929, wherein bunch length sections are separated from a stream of filler tobacco for assembly into a column of tobacco from which bunch charges are separated. In the severance of the bunch length sections the head end of the severed bunch length and the tuck end of the adjoining bunch length section of the filler stream are simultaneously formed by a single cut in order to avoid waste. Since the head end of a blunt head cigar will require more tobacco than its tuck end, the problem of providing the proper amounts of tobacco at the ends of the bunch lengths has been a source of trouble which has been satisfactorily overcome by the present invention.

In some of the cigar machines of this type now in use for manufacturing cigars having blunt heads and tapered tuck ends, the bunch length cutter is shaped to provide at the head end of the severed bunch length the proper amount of tobacco. However, when the shape of the cutter conforms to the desired shape of the head end of the severed bunch length there will be a surplus of tobacco at the tuck end, because the taper on the tuck end of the cigar extends inwardly to a greater distance than the taper on its head end. Accordingly no tobacco will be removed by the cutter at the portion of the tuck end of the bunch length corresponding to the inner portion of the tapered tuck end of the cigar. Therefore, when the tuck end of the cigar bunch formed from the severed bunch lengths was squeezed to the required tapered shape, there was produced a cigar whose tuck end was of greater density than the rest of the cigar and therefore had poor drawing qualities and did not burn evenly. In my prior Patent 1,805,694, there is shown a bunch length cutter which is provided with punches serving to remove the surplus tobacco at the tuck ends of the severed bunch lengths. However when the bunch length cutter of said patent was installed on some cigar machines it was troublesome, because some of the

2

punchings fell on to the bunch lengths and thus were introduced into the finished cigar.

One of the main objects of my invention is to provide a method and apparatus for cutting the bunch lengths in such a manner that the proper amount of filler tobacco required for cigars having blunt heads and tapered tuck ends will be provided at the tuck end, and a surplus of tobacco will be provided at the head end which will be trimmed off from the cigar bunch in the crimper mechanism which squeezes the ends of the cigar bunch to the required shape. Thus when the tuck end of the cigar bunch is squeezed to the required shape its density will be substantially the same as that of the remainder of the bunch and the drawing and burning qualities of the cigar will not be impaired.

Moreover in the case of cigar machines which were not equipped with the punch cutter of my Patent 1,805,694 an untapered portion of the tuck end of the cigar bunch disposed inwardly of the tapered portion was squeezed to a tapered shape in the crimping jaws. Therefore, when the tuck end of the bunch was released from the crimping jaws, said untapered portion of the tuck end would bulge and the wrapper would tear during application to the tuck end of the bunch. With the bunch length cutter of my present invention the taper of the tuck end of the cigar bunch will attain the required shape by the coaction of the crimper jaws, because the surplus on the head end of the bunch length corresponds to the amount of tobacco which should be removed from the portion of the tuck end of the bunch length corresponding to the inner section of the tapered tuck end of the cigar. Accordingly, this portion of the tuck end of the bunch will not swell out beyond the required shape after removal from the crimping jaws and the wrapper will not be torn when applied to the bunch.

With these and other objects not specifically mentioned in view, the invention consists in certain constructions and methods which will be hereinafter described and set forth in the appended claims.

Referring to the drawings, which form a part of this specification and in which like characters of reference indicate the same or like parts:

Fig. 1 is a fragmentary sectional elevation of a cigar filler feed equipped with the improved bunch length cutter and ledger plate;

Fig. 2 is a perspective view on an enlarged scale of the corrugated bunch length cutter and its ledger plate;

Fig. 3 is a plan view of a bunch length severed from the stream of filler tobacco showing its location in the filler stream;

Fig. 4 is a fragmentary end elevation of a suitable crimper mechanism wherein the ends of a cigar bunch formed from the bunch lengths severed by my improved cutter are squeezed to the desired shape and trimmed;

Fig. 5 is a sectional view of the crimper mechanism showing the operation of the crimper trimming knives;

Fig. 6 is a view on an enlarged scale of a cigar bunch after its ends have been squeezed to the shape required for a blunt head and tapered tuck end, this view showing the ends of the bunch before they are trimmed;

Fig. 7 is a view of a bunch length severed by my improved cutter, the surplus material which is trimmed off from its ends being indicated by dotted lines;

Fig. 8 is a view of the cigar formed by my improved method;

Fig. 9 is a fragmentary view on a greatly reduced scale of a bunch rolling table on which the bunch charge formed from the severed bunch lengths is rolled within a binder to provide a cigar bunch.

Fig. 10 is a plan view of the compacted column M formed from bunch lengths L severed from the advancing stream of filler tobacco T.

Referring to Fig. 1 of the drawings, the filler tobacco consisting of stemmed tobacco leaves is placed in the filler feed channel formed by the upper horizontal run of an endless belt 10 and the inner vertical runs of a pair of side belts (not shown) to form a stream of filler tobacco T. Belt 10 and the side belts (not shown) are intermittently driven by suitable mechanism such as shown in the Bronander Patent 1,740,571, wherefore further description thereof is deemed unnecessary. The stream of filler tobacco T is advanced on belt 10 by bunch length increments over a ledger plate 12 supported on a base (not shown) corresponding to the base 71 of said Bronander patent. Thus the leading end of the filler stream is advanced upon a swingable platform 15 (fragmentarily shown), corresponding to the platform 22 of said Bronander patent. The base (not shown) is secured to the lower ends of a bifurcated pedestal 17 whose upper portion is fragmentarily shown in Fig. 1. The pedestal 17 corresponds to the pedestal 17 in the above-mentioned Bronander patent, and reference may be had to said patent for further details thereof. On stationary guide posts 19, which correspond to the posts 70 of said Bronander patent, is slidably mounted a frame 21 to which is secured the corrugated bunch length cutter 23. The cutter 23 is provided with ribs 24 having curved and straight shearing edges (Fig. 2) which fit the curved indentations 13 of the ledger plate 12 when the cutter descends to sever a bunch length L from the filler stream T. The indentations 13 of the ledger plate have a configuration corresponding to the required shape of the head end of the bunch lengths from which the cigar bunch is to be formed, and are provided with inward extensions 14 which fit extensions 25 on the ribs 24 of cutter 23. These indentations 14 and extensions 25 are substantially straight-sided wedges to form the taper at the tuck end illustrated at the left of Fig. 6. Thus when the bunch length L is severed from the filler stream T, as shown in Figs. 3 and 10, the head end of the severed bunch length will

have fish-tails or projections F corresponding to the shape of the ribs 24 and integral extensions E corresponding in shape to the extensions 25 of ribs 24. Since the curve of the projections F is different from the extension E, the shoulder J will be formed at the juncture of the projections F and E. The tuck end of bunch length L will have indentations corresponding to the shape of the fish-tails F and their extensions E. It may be noted that the area of the integral extensions E is approximately equal to the amount of tobacco which should be removed from the tuck ends of the bunch lengths for formation of a tapered tuck end on the final cigar bunch formed from the bunch lengths. Furthermore, the extension E is shaped to make the wedge-like cut H (Fig. 7) so as to provide this taper as illustrated at the left of Fig. 6 when the final cigar bunch is formed.

The frame 21 is connected to a slide 30 corresponding to the slide 60 of the above-mentioned Bronander patent. Slide 30 is mounted between guide rails 32 on pedestal 17 and is connected by a link 34 to a cam lever 36 provided with a cam 25 roller 38 engaging a cam track of a cam 40 mounted on a shaft 42 supported by pedestal 17. Since the mechanism for reciprocating slide 30 is similar to that shown in said Bronander patent, further description thereof is deemed unnecessary except to state it will move cutter 23 downwardly to coact with the ledger plate 12 and thereby sever a bunch length from the stream of filler tobacco T. The compactor 43 is suspended by links 44 and 46 from a bracket 48 of pedestal 17, the joint of links 44 and 46 being connected by a link 50 to slide 30. The compactor 43 is guided in its reciprocating movement by rods 52 which slide in bearings 54 of pedestal 17. Thus the filler stream T is compacted by compactor 43 before it is fed over the ledger plate 12 on to the swingable platform 15.

The severed bunch length rests on the swingable platform 15 which then swings downwardly. A swinging arm (not shown) then advances the severed bunch length sidewise to form a compacted column M of tobacco from which a bunch charge C of tobacco is separated by a suitable knife K. The construction of the swinging arm and the manner in which the column of tobacco is formed and bunch charges separated therefrom is illustrated in the above-mentioned Bronander patent. The separated bunch charges may be delivered manually or by a charge transfer (not shown) to a bunch rolling table of any suitable construction such as shown in the Carlson Patent 2,081,983. In Fig. 9 is fragmentarily shown a portion of the bunch rolling table of the Carlson Patent 2,081,983. Table 7 is provided with a bunch rolling apron 8, and the bunch charge is deposited in a loop formed in apron 8 by a rolling pin 9. As the rolling pin 9 moves forwardly across the table the bunch charge C in its loop is rolled within a binder spread upon the apron in front of the loop, to form a cigar bunch B. The cigar bunch is then transferred to a softening mechanism such as shown in Clausen Patent 2,337,028 from which it is delivered to the crimper mechanism.

In the crimper mechanism illustrated in Figs. 4 and 5, which may be of any suitable construction such as shown in the Bronander Patent 1,578,579, issued March 30, 1926, the ends of the cigar bunch are squeezed to the required shape to provide a blunt head and a tapered tuck end. The crimper mechanism includes a bracket 60 in

which a post 62 is reciprocably mounted. Post 62 carries a head 64 to which are secured a pair of lower crimper jaws 66 spaced sufficiently to engage the ends of the cigar bunch. On a shaft 68 in bracket 60 is secured a swinging bracket 70 provided with a head 72 on which are secured a pair of upper crimper jaws 74. Jaws 74 are complementary to jaws 66 and sufficiently spaced to engage the ends of the cigar bunch when bracket 70 is swung inwardly. An actuator 76, which is shown fragmentarily in Fig. 4, is pivotally mounted on bracket 60 and connected by a link 78 to a boss 80 formed on head 64; and actuator 76 is also connected by a link (not shown) corresponding to the link 10 of Bronander Patent 1,578,579 to a cam lever (not shown). When the actuator 76 is swung on its pivot the post 62 is raised or lowered with the crimper jaws 66.

The actuator 76 is provided with a cam surface (not shown) corresponding to the cam surface 23, 24, shown in Bronander Patent 1,578,579, and engaging a cam follower (not shown) on the lower end of bracket 70. When actuator 76 is rocked to raise the lower crimper jaws 66 to the position shown in Fig. 2 of the Bronander Patent 1,578,579, the arm 70 is swung inwardly with the upper crimper jaws to the position shown in Fig. 2 of said patent and held in this position while the post 62 is further raised with the lower crimper jaws to the uppermost position shown in Fig. 4 of my drawing. A spring (not shown) corresponding to the spring 26 of the Bronander Patent 1,578,579 is connected to arm 70 to maintain the cam follower (not shown) on arm 70 against the cam surface of the actuator 76.

The cigar bunch B is inserted by the bunch transfer of the above-mentioned Clausen Patent 2,337,028 between the crimper jaws while they are in the positions shown in Fig. 1 of Bronander Patent 1,578,579. The actuator 76 is then rocked and the post 60 is raised with the crimper jaws 66 while arm 70 is swung inwardly with crimper jaws 74 and the jaws 66 are further raised to the position shown in Fig. 4. The ends of the cigar bunch B are thus squeezed between the crimper jaws to substantially the shape shown in Fig. 6 whereby a teat S is formed on the head end of the bunch B.

Referring again to Fig. 3 hereof it will be noted that the extensions E on the fish-tails F of the severed bunch lengths form the teat S on the head end of the cigar bunch B when squeezed between the crimper jaws 66 and 74. The shape of the fish-tails F of the severed bunch lengths can be varied to suit various shapes of blunt heads desired on the cigar bunch by varying the shape of the ribs 24 of cutter 23. The shape of the extensions E on the fish-tails F of the severed bunch length may be varied by changing the shape of the extensions 25 on the ribs 24 of cutter 23. However the area of ribs 24 and extensions 25 should be great enough to remove sufficient material from the tuck ends of the bunch lengths to provide the requisite taper of the tuck end of the cigar bunch when squeezed between the crimper jaws. It should also be noted that the extensions E of fish tails F should extend into the tuck end of the adjoining bunch length section of the filler stream to a point where the taper of the tuck end of the cigar bunch practically terminates. Thus the bulging of the tuck end of the cigar bunch B upon being released from the crimper jaws will not make it oversize, as in the case of some cigar machines now in use for manufacturing blunt head cigars. Therefore the tuck end of the cigar bunch B will be of the

proper size and will not tear the wrapper during application to the bunch in the wrapping mechanism.

The bunch crimping mechanism is further provided with mechanism for trimming the ends of bunch B after they have been squeezed to the proper shape by the crimper jaws 66, 74. This mechanism includes a pair of trimming knives 82 fastened to the upper ends of a pair of arms 84 secured to the shaft 68. One of the arms 84 has an extension 86 which lies in the path of a stud 88 secured to the actuator 76. A stop screw 90 threaded into a boss 92 on the arm 70 limits the movement in one direction of the arm 84 having the extension 86, and this arm is normally held against screw 90 by a compression spring 94.

When the parts of the crimper mechanism have reached the position shown in Fig. 4 hereof, the crimper jaws 66 and 74 remain stationary for reasons fully described on page 2, lines 55-61 of the specification of Bronander Patent 1,578,579. At this time the stud 88 has come into engagement with the extension 86 of arm 84 and a little further rocking movement of the actuator 76 throws the trimming knives into operation. The teat S is thus severed from the head end of the cigar bunch B and its tuck end is simultaneously trimmed. When the actuator 76 is rocked in the opposite direction the trimming knives are first returned to their normal position, then the post 62 is lowered and the bracket 70 swung outwardly to release the shaped bunch. A suitable bunch transfer then carries the bunch to the wrapper applying mechanism where the wrapper is applied to form the finished cigar C shown in Fig. 8.

It will be observed that the ends of the bunch B are trimmed in the crimping mechanism from the shoulders J along the dotted lines A—A and D—D in Fig. 7 to form the blunt head of the cigar bunch and the desired taper of its tuck end.

What is claimed is:

1. In a cigar machine for making cigar bunches having a tapered tuck end, the combination with bunch crimper mechanism adapted to shape and trim the ends of cigar bunches, said bunch crimper mechanism including a pair of jaws adapted to compress the tuck ends of cigar bunches to a predetermined tapered shape, means for forwarding a narrow stream of filler tobacco, a ledger plate over which said stream of filler tobacco is advanced by said means for severance of bunch lengths, said ledger plate being provided with indentations having curved sides and having a configuration corresponding to the required shape of the head ends of bunch lengths from which cigar bunches are to be formed, the indentations in said ledger plate having inward substantially wedge-shaped extensions, and the configuration of said indentations and their inward extensions corresponding to the required shape of the indentations in the tuck ends of bunch lengths from which cigar bunches are to be formed and said inward extensions terminating at a point where the taper of the tuck ends of cigar bunches formed therefrom substantially terminates when the cigar bunches are compressed between said pair of jaws, and a cutter provided with ribs closely fitting the indentations of said ledger plate and their inward extensions and adapted to coact therewith to sever bunch lengths of filler tobacco from said stream and which are assembled for the formation of bunch charges to which binders are applied to produce cigar bunches, whereby the head end

of the severed bunch length section will have the proper amount of tobacco required for formation of the head end of the cigar bunch and a surplus of tobacco consisting of integral tails which will be trimmed off in said bunch crimper mechanism when said cigar bunches are delivered to the crimper mechanism, and the tuck end of the bunch length section of the filler stream located immediately behind the cutter will have the proper amount of filler tobacco required for the formation of the tapered tuck end of the cigar bunch.

2. In a cigar machine, the combination with a ledger plate over which a stream of filler tobacco is advanced for severance of bunch lengths, a cutter adapted to coat with said ledger plate to shear bunch lengths from said stream, said ledger plate having extended indentations along only one lateral edge thereof and said cutter having ribs closely fitting said extended indentations of the ledger plate, said indentations each having a major curved portion adjacent the open end thereof and a minor portion at the inner end thereof and of a contour differing from that of the major portion and said extended indentations and ribs having a configuration and area which will provide fishtails on the head end of the severed bunch length containing sufficient tobacco for formation of blunt heads on cigar bunches formed from the severed bunch lengths together with a surplus of tobacco consisting of integral tails projecting from said fishtails into the tuck end of the adjoining bunch length section of the filler stream, the length and width of said tails being sufficient that the amount of tobacco therein will approximately equal the amount of tobacco which should be removed from the tuck end of the bunch lengths for formation of the taper of the tapered tuck end on the cigar bunch formed from said bunch lengths.

3. The method of forming cigar bunches from which cigars having tapered tuck ends are to be formed, comprising forming a stream of long filler tobacco, making a single corrugated cut having curved portions and wedge-shaped extensions on each curved portion and forming shoulders between said portions and extensions, across the stream at intervals of a bunch length apart and thus simultaneously severing bunch lengths and forming the head and tuck ends of adjoining bunch length sections with a series of projections at each end of the severed bunch lengths, the shape of the cuts being such that the requisite amount of filler at the tuck end of the severed bunch lengths will be provided and a surplus amount of tobacco will be provided on the extremities of the projections at the head end of the severed bunch lengths, forming a bunch charge from the bunch lengths, wrapping the bunch charge in a binder to form a cigar bunch, squeezing the ends of the cigar bunch to form a tapered tuck end having the tapered shape required and also form a head end having a projecting teat, the surplus material on the head end of the bunch charge constituting said teat, and then trimming the projecting teat on the head end of the cigar bunch and also trimming the tuck end of the bunch.

4. In a cigar machine, the combination with a ledger plate over which a narrow stream of filler tobacco is advanced for severance of bunch lengths, said ledger plate being provided with

indentations having a configuration corresponding to the required shape of the head ends of bunch lengths from which cigar bunches having blunt head ends are to be formed, the indentations in said ledger plate having inward extensions and the configuration of said indentations and their inward extensions corresponding to the required shape of the tuck ends of bunch lengths from which cigar bunches having tapered tuck ends are to be formed, said indentations and extensions forming inwardly directed shoulders at the juncture of each indentation and its extension and said inward extensions of said indentations projecting into the tuck end of the adjoining bunch lengths in said stream to a point where the taper of the tuck end of the cigar bunch formed from said bunch length substantially terminates, and a cutter provided with ribs closely fitting the indentations of said ledger plate and their inward extensions and adapted to coat therewith to sever bunch lengths of filler tobacco from said stream, whereby the head end of the severed bunch length section will have the proper amount of tobacco required for the formation of the blunt head end of the cigar bunch and a surplus of tobacco consisting of integral tails, and the tuck end of the adjoining bunch length section of the filler stream located immediately behind the cutter will have the proper amount of filler tobacco required for the formation of the tapered tuck end of the cigar bunch.

5. The method of forming cigar bunches from which cigars having blunt heads and tapered tuck ends are to be formed, comprising forming curved and substantially straight cuts along a predetermined line across a stream of long filler tobacco by a single corrugated cutting operation at intervals of a bunch length apart and thus simultaneously forming the head and tuck ends of adjoining bunch length sections to provide a series of projections at each end of the severed bunch lengths, the shape of the cuts being such that the requisite amount of filler for the formation of the blunt head and tapered tuck end of a cigar will be provided at the ends of the severed bunch lengths and a surplus amount of tobacco will be provided at the extremities of the projections at the head end of the severed bunch lengths, assembling the bunch lengths to form a bunch charge, wrapping the bunch charge in a binder to form a cigar bunch, squeezing the ends of the cigar bunch in a bunch crimper mechanism to form a tapered tuck end corresponding to the tapered shape required and also form a blunt head end having a projecting teat, and trimming off said teat in the crimper mechanism, said surplus amount of tobacco on the head end of the bunch length constituting said teat.
